UNITED STATES PATENT OFFICE.

HENRY JANSSEN, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING CARRIER.

Application filed January 5, 1927. Serial No. 159,053.

My invention relates to braiding carriers which employ a pawl-controlled bobbin; and it consists in improved thread tensioning means mounted upon the base portion of the carrier and comprising a thread-operated tensioning lever and a bobbin-releasing pawl lever cooperatively arranged, as fully set forth in connection with the accompanying drawings, the novel features being clearly defined in the subjoined claims.

Fig. 1 is a front view of a carrier embodying my invention; the bobbin spindle being partially broken away and the ratchet wheel shown in cross-section, and a filled bobbin being indicated in dotted outline.

Fig. 2 is a side view looking in the direction of the arrow in Fig. 1.

Fig. 3 is a sectional plan view, taken on the line 3—3 of Fig. 1.

Fig. 4 is a vertical-section view on the line 4—4 of Fig. 3, looking in the direction of the arrow; the scale being enlarged.

The lower portion or base of the carrier comprises the usual plate-engaging foot, with a standard 6 having a fixed bobbin-supporting stem 7 rising therefrom, and a parallel thread-guide upright 8. Upon the stem 7 is rotatably mounted the bobbin spindle 10, having a fixed ratchet wheel 11 at its base and above the standard 6; the bobbin 12, indicated in dotted outline, being tight upon the rotatable spindle and the thread passing therefrom through guide eye 8^a to the tensioning mechanism.

In my improved construction the base standard 6 is formed with a tensioning-spring cylinder 15 arranged transversely of the bobbin spindle, and is provided with a tensioning lever 16 which is pivotally mounted concentric with said cylinder and has a thread-engaging end portion 16^a. As shown this lever is formed with a fork-head which spans the base standard 6, and its separated arms 16^b, 16^c are pivotally mounted on the projecting ends of a bushing sleeve 17 in the cylinder 15, with the connected tensioning spring 20 in the latter operating to swing downward the thread-engaging end 16^a of the lever; the normal tensioning of the spring being readily varied by means of a rotatable spring-engaged cap 21 having a pin 22 adapted to be set into engagement with one or another of a corresponding circular series of holes in the adjacent lever arm 16^b—the opposite end of the coiled

spring being fixedly connected as indicated to a notched spring-supporting screw 23 secured to a bracket 24 of the base standard.

The tensioning lever 16 is adapted to operate a bobbin-releasing pawl lever 25, which is also pivoted concentric with the tensioning-spring cylinder 15 and has its pawl arm 25^a normally swung into engagement with the bobbin ratchet wheel 11 by a spring-pressed plunger device 26 bearing against an oppositely extending arm 25^b; this pawl lever being releasably operated by the lifting of the tensioning lever 16 when more thread is needed. As shown, the pawl lever 25 is pivotally mounted midway between the fork-head pivoting portions 16^b of the tensioning lever 16, upon the bushing sleeve 17 in the tensioning-spring cylinder, the latter being provided with a midway vertical slot to receive it; and it is formed with a lateral projection or projections 25^c so arranged as to contact with an operating offset or offsets 16^d on the tensioning lever 16 when the latter is being fully raised by the pull of the thread. The lateral projections 16^d on the tensioning lever merely serve to automatically operate a stop mechanism in case of thread breakage.

The preferred construction specifically set forth may obviously be readily modified without departing from the invention as defined in the claims.

What I claim is:

1. In a carrier having a rotatably mounted ratchet-controlled bobbin; a carrier base having a cylindrical tensioning-spring chamber arranged transversely of the bobbin, a bobbin-engaging pawl lever and a thread-operated pawl-releasing lever both pivotally mounted concentric with said transverse spring chamber, and a tensioning spring in said chamber operating upon said pawl-releasing lever.

2. In a carrier having a rotatably mounted ratchet-controlled bobbin; a carrier base having a cylindrical tensioning-spring chamber arranged transversely of the bobbin, a bobbin-engaging pawl lever and a thread-operated pawl-releasing lever both pivotally mounted concentric with said transverse spring chamber, a spiral spring in said chamber operatively connected to said pawl-releasing lever, and a spring-tensioning chamber cap adjustably engaging said lever.

3. A carrier for a ratchet-controlled bobbin having a foot portion, a fixed standard thereon the upper portion of which forms a bobbin support and the intermediate portion of which is formed with a transversely arranged tensioning-spring chamber, a bobbin-releasing pawl lever pivotally mounted concentric with said transverse chamber, a tensioning spring mounted in said chamber, and a tensioning lever also pivotally mounted concentric with said chamber and operative upon said pawl lever under control of said spring.
4. A carrier for a ratchet-controlled bobbin having a foot portion, a fixed standard thereon the upper portion of which forms a bobbin support and the intermediate portion of which is formed with a transversely arranged tensioning-spring chamber, a bobbin-releasing pawl lever pivotally mounted concentric with said transverse chamber, a tensioning spring mounted in said chamber, and a tensioning lever also pivotally mounted concentric with said chamber and oper-

tive upon said pawl lever under control of 25 said spring, said transverse chamber having a spring-enclosing cylindrical bushing upon which both said levers are pivotally mounted.

5. A carrier for ratchet-controlled bobbin having a foot portion, a fixed standard 30 thereon the upper portion of which forms a bobbin support and the intermediate portion of which is formed with a transversely arranged tensioning-spring chamber, a bobbin-releasing pawl lever pivotally mounted 35 concentric with said transverse chamber, a tensioning spring mounted in said chamber, and a tensioning lever also pivotally mounted concentric with said chamber and operative upon said pawl lever under control of 40 said spring, said transverse chamber having a spring-enclosing cylindrical bushing, and said pawl lever and tensioning lever being pivotally mounted upon the midway portion 45 and end portion respectively of said bushing.

In testimony whereof I affix my signature.

HENRY JANSSEN.
